UNITED STATES PATENT OFFICE.

HARRY H. HORNSBY, OF CHICAGO, ILLINOIS.

DISTRIBUTING-BOX.

No. 833,827.

Specification of Letters Patent.

Patented Oct. 16, 1908.

Application filed January 7, 1903. Serial No. 138,107.

To all whom it may concern:

Be it known that I, HARRY H. HORNSBY, a citizen of the United States, residing at Chicago, in the county of Cook and State of Illinois, have invented a certain new and useful Improvement in Distributing-Boxes, of which the following is a full, clear, concise, and exact description, reference being had to the accompanying drawings, forming a part of this specification.

My invention relates to improvements in distributing-centers. These devices as now constructed consist usually of a box in which is suitably supported a panel-board of insulating material. Contact-bars are mounted upon the panel-board and the mains or supply-wires are suitably connected therewith. Also upon said panel-board are a plurality of binding-posts connected to said contact bars or strips in any desirable manner. The conduits for the various circuit-wires are brought to the box, and from there the circuit-wires extend unprotected from one another to the various binding-posts. If one of the circuit-wires burns out, the others are also burned.

It is the object of my invention to protect the wires of the different circuits from one another to prevent the destruction of the wires of several circuits in the event of one burning out.

Another object is to keep the wires of the various circuits distinct from one another, so that a particular circuit may be readily located.

A still further object of my invention is to provide conduits for the several circuits leading to a point in proximity to the place of attachment of the circuit-wires upon the panel in order that said wires may be inserted into and extracted from the conduits with facility.

To these ends my invention consists of the details of construction, arrangement, and combinations of parts, as hereinafter described, and pointed out in the claims.

In the accompanying drawings the various views are as follows: Figure 1 is an elevation of my improved distributing-center. Fig. 2 is a cross-sectional view on the line *x* *x* thereof. Figs. 3 and 4 are elevations of the corresponding faces of the sections forming my improved panel-board. Fig. 5 is a longitudinal sectional view through the panel-board. Fig. 6 is an upper edge view thereof. Fig. 7 is a perspective view of another form of my distributing-center. Fig. 8 is a broken sectional view taken through the panel-board

employed in this construction: Fig. 9 is an elevation of a portion of this panel-board, and Figs. 10 and 11 are side and front views of one of the pipes used in this form of panel-board.

Throughout the drawings like reference characters designate similar and corresponding parts.

In one manner of carrying out my invention, as illustrated in the drawings, upon a board 2, of, preferably, insulating incombustible material, are mounted conducting-bars 3. Said bars are connected at one end with binding-posts 4 by fuse-wires 5, and in said board near the binding-posts are provided holes or apertures 6. A plurality of pairs of contact-strips 7 are arranged upon said board transverse to the conducting-bars 3. Each of the contact-strips is in contact with either one or the other of the conducting-bars, and the arrangement is such that the contact-strips of each pair engage different conducting-bars. Each end of the several contact-strips is connected by a fuse 8 with one side of a switch 9. The outer side of each of said switches is provided with a binding-post 10. To the binding-posts on one side of each pair of contact-strips are connected the wires 11 of each branch circuit, and a hole 12, through which the wires 11 are passed, is provided in said board in proximity to each pair of binding-posts for the several circuits. A casing 13 is arranged around said board in any desirable manner for inclosing the same and the various parts mounted thereon. The back of said board is provided with a number of grooves or channels 14, each of which leads from one of the holes 12 in said board to the edge thereof. In the drawings are shown five holes for the circuit-wires arranged upon each side of the conducting-bars. The channels leading to the two upper holes on each side run to the top edge of the board and toward the center thereof, and the holes leading from the lower two holes on each side run to the lower edge of the board and also toward the center thereof. The channel for the other hole on each side of the board leads to the side of the board corresponding therewith.

A board 15 is secured upon the back of the board heretofore referred to in any suitable manner. Said back board has its meeting face grooved or channeled to correspond to the front board. The channels or grooves of the two boards are so formed and of such

cross-area that they provide smooth, preferably circular, passages from the holes in the front board to the edges thereof. The conduits for the several branch circuits each 5 communicate with one of said passages in such manner that a continuous passage is provided from the hole in the outer board to the end of the conduit.

By my construction the wires of the various circuits are thoroughly protected one from the other, and therefore the burning of one circuit will not destroy the others. Also the various circuits may be readily located, and in addition to this the wires may be inserted or extracted from their respective passages with facility. If it be desired to put in a wire, it may be pushed in through the proper hole in the outer board and it will work its way to the end of the conduit.

Again, if the wire be started in at the outer end of the conduit it will come out of the corresponding hole in the outer board in proximity with its point of attachment upon said board.

The passages between the boards are constructed, preferably, without projections, so that the end of a wire passing in either direction will not be obstructed or caught in its passage, and also the connection between said passages and their respective conduits is made smooth for the same reason. Both of the boards also have their meeting faces provided with corresponding grooves 16, extending entirely across the boards and forming a passage through which the main supply-wires 17 pass. The binding-posts for the conducting-bars are connected with the main supply-wires by wires 18, which pass through the opening provided therefor.

In the construction illustrated in Figs. 7, 8, 40 9, 10, and 11 in lieu of forming the passages to the holes by grooves in boards a series of pipes 19 is provided, which communicate with the holes. Said pipes extend straight down 45 from the edge of the board, and the holes with which they communicate are disposed accordingly. A board 20, bolted to the front board, clamps said pipes in position. Said pipes have their outer ends extended through 50 the casing and are provided with collars 21 to prevent displacement of the pipes, and the conduits 22 are connected with said pipes by threaded sleeves 24.

The construction which I have provided 55 may be set in the same space as the distributing-centers at present in use. This could not be done if it were attempted to extend the circuit-conduits directly to the point of attachment for the wires, as considerable space would be required in order to properly adjust the conduits in position.

I am aware that various changes may be made in the details of construction herein shown and described without in any way departing from the spirit of my invention, and

I therefore reserve the right to make such modifications as fairly fall therein.

Having described my invention, what I claim as new, and desire to secure by Letters Patent, is—

1. In a device of the character described, in combination, a distributing-board provided with a plurality of apertures in the face thereof, terminals arranged adjacent to said apertures, passage-ways arranged in the interior of said board and leading from said apertures to the edges of said board whereby the wires of main and branch circuits may be readily passed through said passage-ways to connect them with the terminals on the 75 board and whereby the said wires are inclosed and fixedly isolated from each other.

2. In a device of the character described, in combination, a distributing-board consisting of a front board and a back board, the 80 front board being provided with a plurality of apertures in the face thereof, terminals arranged adjacent to said apertures, passage-ways arranged interiorly between said boards and leading from said apertures to the edges 85 of said board whereby the wires of main and branch circuits may be readily passed through said passage-ways to connect them with the terminals on the front board and whereby the said wires are inclosed and fixedly isolated from each other.

3. In a device of the character described, in combination, a distributing-board consisting of a front board and a back board fastened together, said front board being provided with a plurality of apertures in the face thereof, terminals arranged adjacent to said apertures, passage-ways, substantially parallel to the face of the distributing-board, arranged interiorly between said front and 100 back boards and leading from said apertures to the edges of said distributing-board whereby the wires of main and branch circuits may be readily passed through said passage-ways to connect them with the terminals on the front board and whereby the said wires are inclosed and fixedly isolated from each other.

4. In a device of the character described, in combination, a distributing-board consisting of a front board and a back board fastened together, said front board being provided with a plurality of apertures in the face thereof, terminals arranged adjacent to said apertures, passage-ways arranged interiorly between said front and back boards and leading from said apertures to the edges of said distributing-board, whereby the wires of main and branch circuits may be readily passed through said passage-ways to connect them with the terminals on the front board 115 and whereby they are inclosed and fixedly isolated from each other, and means, including protective devices, arranged on the face of the front board, for connecting the branch circuits with the main circuit.

5. In a device of the character described, in combination, a distributing-board consisting of a front board and a back board fastened together, said front board being provided with a plurality of apertures in the face thereof, terminals arranged adjacent to said apertures, passage-ways arranged interiorly between said front and back boards and leading from said apertures to the edges of said 10 distributing-board whereby the wires of main and branch circuits may be readily passed through said passage-ways to connect them with the terminals on the front board,

and whereby the said wires are inclosed and fixedly isolated from each other, means, including protective devices, arranged on the face of the front board for connecting the branch circuits with the main circuit, and a suitable inclosing casing. 15

In witness whereof I have hereunto subscribed my name in the presence of two witnesses. 20

HARRY H. HORNSBY.
